ABSTRACT: A warp beam of a considerable length for a loom which has a plurality of warping drums thereon and is centrally divided so as to form a pair of shorter rollers which are pivotable at their outer ends relative to each other within a horizontal plane and are adapted to be rotatably mounted at their inner ends so as to extend coaxially to each other when in their operative position in which they are driven synchronously.

WARP BEAM ARRANGEMENT

The present invention relates to a warp beam arrangement for a loom and especially for a loom for producing metal cloth, wherein the warp beam is provided with a plurality of warping drums carrying the warp wires which are adapted to be mounted on the beam so as to be slideable thereon but to be nonrotatable relative thereto.

In warp beam arrangements as heretofore known the beam itself without the warping drums consists of a single piece of material. As the weaving width increases, the size and weight of a warp beam increases to such an extent that various disadvantages occur. Since for preventing the warping drums from rotating on the warp beam, the latter has to be provided with a longitudinal groove into which guide rails engage which are secured to the inner wall of the warping drums, it is only possible to produce the warp beams by casting which, when the beam has to have a very great length of, for example, 10 meters or more, causes considerable casting difficulties. Furthermore, for taking up the forces acting upon the warp beam so that the latter will run smoothly, it would be necessary to make the warp beam of an excessive wall thickness.

It is an object of the present invention to provide a warp beam of a great length which overcomes the above-mentioned disadvantages. According to the invention, this object is attained by dividing the warp beam at the center of its length so as to form two rollers, by mounting these rollers on their outer ends so as to be pivotable within a horizontal plane, by driving the rollers synchronously, and by rotatably mounting them at their inner ends where they are divided from each other so that, when this warp beam arrangement is in its operative position, the rollers extend coaxially to each other.

The bearing means for mounting the two rollers at their place of division are preferably designed so that the ends of the rollers facing each other are spaced at a certain distance from each other, that in this space the bearings are mounted which are supported by a disk-like upright which projects through and from this space, and that the spaces between the upright and the adjacent ends of the rollers may be covered by the warping drums which are slideable in the axial direction along the warp beam.

When unwinding the warp wires from the warping drums near the place of the division between the rollers, there will thus be only a very small distance between the two warp wires at both sides of the place of division which space will decrease during the distance of travel from the warp beam to the loom to the same size as that between the other warp wires.

The disk-like upright preferably carries within the inner diameter of the rollers a two-piece support for two bearings in which the journals of the rollers are rotatably mounted. This support is easily accessible through the space between the two rollers.

The features and advantages of the present invention will become further apparent from the following detailed description thereof which is to be read with reference to the accompanying drawings, in which:

FIG. 1 shows a top view of the warp beam arrangement according to the invention;

FIG. 2 shows a vertical axial section of a part of the warp beam arrangement according to FIG. 1;

FIG. 3 shows a side view of the upright; while

FIG. 4 shows a vertical section of a warp beam with a warp drum thereon.

According to the invention, the warp beam which preferably consists of cast iron is divided at the center of its length into two rollers 1 and 2, the outer journals 3 of which are rotatably mounted in bearings 4 each of which is pivotable in a manner known as such about a vertical axis which intersects the axis of the bearing.

On each journal 3 a worm wheel 5 is secured which may be driven by a worm 6. As shown at the right side of FIG. 1, the worm wheel 5 on each roller 1 and 2 will temporarily disen-

gage from the associated worm 6 when the roller is pivoted out of its operative position. Worms 6 are secured to shafts 7 one of which forms the main drive shaft for the warp beam 1, 2. For driving the two rollers 1 and 2 synchronously, each shaft 7 carries a bevel gear 8 which meshes with another bevel gear 9. The two bevel gears 9 are connected to each other by a shaft 10 which is mounted in bearings 11 which, in turn, are mounted on brackets 24 on the frame 23 of the warp beam arrangement.

10 The ends 12 and 13 of rollers 1 and 2 facing each other are spaced at a distance *a* from each other, as shown in FIG. 2. The space 14 which is formed by this distance *a* contains bearings 15 and 16 which are mounted on a disk-like upright 17 which projects from this space 14. Upright 17 is provided with a foot 19 which is secured by bolts 20 to a bottom rail 18, and it is further provided within the space 14 with a hub 25 and 25' the two parts of which are connected to each other by screws 29. Bearings 15 and 16 which preferably are roller or ball bearings support the journals 26 and 27 of rollers 1 and 2. Said journals are firmly secured in removable sockets 28 each of which is connected to the associated roller 1 or 2 by screws, not shown. The disk-like upright 17 has a lateral part 21 which is secured by screws 22 to the frame 23 for supporting the warp beam arrangement.

25 Warp beam 1, 2 carries warping drums 30 which are preferably made of steel and have an inner diameter equal to the outer diameter of warp beam 1, 2 and a U-shaped cross section. On these warping drums 30 the warp wires 31 are wound. The outer surface of warp beam 1, 2 is provided with a longitudinal groove 32 into which, when a warping drum 30 is slipped over the warp beam 1, 2, a U-shaped rail 33 engages which is secured to and projects from the inner wall surface of each warping drum 30 (FIG. 4). Since the warp beam 1, 2 is provided along the length of its groove 32 with an inwardly reinforced part 34, it has on its diametrically opposite side a balancing weight 35.

30 The warping drums 30 are slideable in the axial direction along the rollers 1 and 2 each of which has a sufficient length to receive the required number of warping drums, even if the end surfaces of the drums which are capped on last are in alignment with the end surfaces 12 and 13 of rollers 1 and 2. After the rollers 1 and 2 are pivoted so as to extend coaxially, the warping drums 30 are shifted to the position as shown in FIG. 2, in which they are located closely adjacent to the upright 17 and substantially cover the space 14 between the ends of rollers 1 and 2. As shown at the left side of FIG. 1, a space *b* is available between the worm wheels 5 and the group of warping drums on each roller 1 and 2.

35 40 45 50 Rollers 1 and 2 may be pivoted within a horizontal plane by means of an auxiliary carriage of a conventional type which may be movable along a portable rail 36.

55 Although our invention has been illustrated and described with reference to the preferred embodiment thereof, we wish to have it understood that it is in no way limited to the details of such embodiment but is capable of numerous modifications within the scope of the appended claims.

We claim:

1. A warp beam arrangement subjected to great forces and comprising:
  - two rollers each being adapted to support a plurality of warping drums and both being rotatably mounted coaxially to each other when in their working position and adapted to be driven synchronously so that both rollers together form a warp beam;
  - each of said rollers having an outer end and an inner end facing the inner end of the other roller, the outer end of each roller having an outer journal;
  - a first bearing for rotatably mounting said outer journal;
  - said first bearing being pivotable about a vertical axis intersecting the axis of said first bearing so that each roller is pivotable about the associated vertical axis;
  - said inner ends of said rollers being spaced at a short distance from each other so that a gap is formed between said inner ends;

two inner journals at each of said rollers, respectively, and projecting from said inner ends, respectively, into said gap towards each other but spaced slightly apart from each other;

two second bearing means coaxially aligned within and substantially covering the width of said gap for rotatably mounting of said inner journals of each of said rollers, respectively, and an upright supporting said second bearings and extending through said gap, said upright comprising two parts adapted to be separated from each other so as to permit said inner journals and the inner end of each of said rollers together with the associated second bearing means to be separated from said upright; and said warping drums being slideable in the longitudinal direction along said warp beam so that said gap is covered substantially by said warping drums up to said upright.

2. A warp beam arrangement as defined in claim 1, further comprising a worm wheel mounted on and secured to each of said journals, a pair of shafts extending parallel to each other and at a right angle to the common axis of said rollers, one of said shafts being adapted to be driven, a worm secured to each of said shafts and meshing with one of said worm wheels, a

first bevel gear secured to each of said shafts, a connecting spindle, and a pair of second bevel gears secured to the outer ends of said connecting spindle and each meshing with one of said first bevel gears.

5 3. A warp beam arrangement as set forth in claim 1, further comprising:

means for releasably mounting a plurality of warping drums on said rollers constituting rail and groove formations; and

10 two of said plurality of warping drums positioned in said working position overlapping said inner ends of said rollers.

4. A warp beam arrangement as defined in claim 1, wherein said upright comprises a disk extending through said gap and

15 having a hub, said disk together with said hub being divided into two parts, means for connecting said parts to each other and for releasing them from each other, said hub projecting in the axial direction from said disk and being adapted to receive said second bearings, said disk having a lower end adapted to

20 be secured to a floor and a lateral part adapted to be secured to a frame for supporting said warp beam arrangement.
